UNITED STATES PATENT OFFICE.

JAMES M. MILLER, OF PERRY, OKLAHOMA.

UNDERREAMER.

Application filed January 6, 1926. Serial No. 79,634.

The object of this invention is to provide an underreamer for use at the lower end of a well casing, or the like, in well known manner, the device including a body provided with a vertical bore and with lateral vertically extending slots thru which the cutting devices extend, and slots in which mandrel engaging and retaining means are mounted, in the special manner hereinafter disclosed.

A further object is to provide for the formation of the openings in the body in such manner that the operative elements will serve the purpose for which they are intended, and for which they are specially constructed, in the most effective manner.

With the foregoing and other objects in view, the invention consists in the novel construction and arrangement of elements described, illustrated and claimed, it being understood that modifications may be made within the scope of the claim, without departing from the spirit of the invention.

In the drawings forming part of this application,

Figure 1 shows the device in side elevation.

Figure 2 is a view in vertical section, the section being on line 2—2 of Figure 1.

Figure 3 is a vertical section, in the same plane, the cutting devices being in operative position.

Figure 4 is a vertical section on line 4—4 of Figure 2.

The body 10 may be provided with an upwardly extending threaded portion 11 for connection with the operating element 12, and said body 10 is formed with a vertical or longitudinal bore 13, the lower end being formed as shown at 14 where a reduced opening 15 is provided, for the purpose indicated below.

The mandrel 16 includes a reduced portion or shank 17 encircled by a coiled spring 18, the upper end of which bears against the under side 19 of the element 16. The lower end of spring 18 bears on the upper portion of element 14 in the manner shown in each of the views in vertical section. Stem or shank 17 may have threaded into the lower end thereof the shank portion of an operating element 20, as shown in Figure 4.

The cutting devices 24 each include an edge portion 24' adapted to extend beyond the lower end of the well casing, shown in dotted line in Figure 3 and designated 25. These devices 24' further include shoulder

27 adapted to engage the wall 28 at the bottom of each vertical slot 29, and the inner sides of elements 24 are adapted to contact with the tapered portions 30 of the body 10, when the cutters 24 are in closed or inoperative position.

The cutters further include the upwardly extending portions or shanks 32 having slots 33 formed therein, the slots accommodating a transverse pin 33' which is threaded into the mandrel 16, the pin having slots in the opposite ends thereof in order to provide for correct adjustment, by the insertion of a tool.

Each cutting device 24 is formed with an upper and outer curved portion 36 adapted to cooperate with the concave portion 37 at the upper wall of each vertical slot 29, the cooperating portion being especially illustrated in Figure 3. The edge portions at the upper ends of the slots are further curved in a reverse direction with reference to the curved portion 37, in the manner shown at 39.

Retaining devices, for holding the mandrel 16 in the position of Figure 4, and against the expansive action of spring 18, are designated 40 and 41, these devices being pivoted at 42 in slots, such as 43, extending radially with reference to the bore 13, the inner ends of devices or dogs 40 and 41 engaging the mandrel when the cutting devices 24 are inoperative.

Locking devices for the dogs are designated 45, and are pivoted at 46 and are movable outwardly under the action of flat spring 47, being guided by pins passing thru slots 48. The retaining devices 45 are automatically released when the body 10 drops to a point in the casing, so that these members 45 project below the bottom of the casing 25. This releases the dogs 40 and 41, and the mandrel 16 moves upwardly under the expansive force of spring 18, and the cutters 24 move outwardly to the position of Figure 3, the co-operating portions 36, 37 and 39 at the upper walls of the vertical slot 29 facilitating the movement of the cutters to operative position.

It will be observed that the contact between surfaces 36, 37 and 39 approaches cam action.

Spring 18 is compressed by pulling down on element 20, and the mandrel 16 moves downwardly engaging the upper curved surfaces of dogs 40 and 41, forcing these dogs outwardly and permitting the mandrel to

pass to the position of Figure 4. In this operation the dogs first move outwardly, being pivoted in the slots 43 of the devices 45, and then said dogs and devices 45 move inwardly, the dogs engaging the mandrel, and the cutters being in the position of Figure 2, so that the whole mechanism may pass without difficulty thru the well casing, until release is effected automatically at the lower 10 end of the casing, as described, because springs 47 are free to act and carry the dogs outwardly for releasing the mandrel 16, so that the latter and the cutters 24 may move to the position of Figure 3.

15 Having thus described the invention, what is claimed as new, is:

In a device of the class described, a body having a vertical bore and having slots com-

municating with the bore, cutting devices within the slots and adapted to bear against the upper walls thereof, the cutting devices including upper slotted portions, a mandrel within the bore and means on the mandrel for engaging the slotted portions last named, means for retaining the cutting devices inactive, and a spring for moving the mandrel and cutting devices upwardly and outwardly upon release by the retaining means, said retaining means including pivoted dogs and pivoted spring actuated devices mounting the dogs, these devices having guiding slots, and pins passing transversely thru the slots and into the body portion.

In testimony whereof I affix my signature.

JAMES M. MILLER.
